UNITED STATES PATENT OFFICE.

WILSON WORTH BURSON, OF ROCKFORD, ILLINOIS.

KNITTING-MACHINE.

1,025,182.

Specification of Letters Patent.

Patented May 7, 1912.
Application filed January 2, 1908. Serial No. 408,992.

To all whom it may concern:

Be it known that I, WILSON WORTH BURSON, a citizen of the United States, residing at Rockford, in the county of Winnebago and State of Illinois, have invented a new and useful Improvement in Knitting-Machines, of which the following is a specification.

My invention relates to improvements in straight knitting machines having two parallel rows of needles mounted on suitable frames with an opening between them for the knit fabric to pass through, and the object of my invention is to simplify the construction and improve the operation of the knitting machine, as will appear in the description of the parts. I attain this object by the mechanism illustrated in the accompanying drawings in which,

20 Figure 1 shows an end elevation, certain parts being omitted; Fig. 2 is a top plan view; Fig. 3 shows the pattern operating parts; Figs. 4 and 5 show details of the same; Figs. 6 and 7 show end and side elevations 25 of the patterns; Fig. 8 shows a section of the needle bed and of the pattern; Fig. 9 is an enlarged detail section of the needle controlling mechanism out of action; Fig. 10 shows a bottom plan of one of the knitting 30 cams; Fig. 11 is a longitudinal section of said cam showing the adjusting devices; Fig. 12 shows the pattern controlling devices; Figs. 13 and 14 are detail views of the switch wheel 20, showing the parts in different 35 positions; Fig. 15 is a detail side elevation of a portion of the mechanism for effecting the interchange of the guide carriers.

Similar letters refer to like parts throughout the several views.

40 In the drawing, 1 is the supporting base; 2 is the frame to which the operating parts are mainly attached; 3 is a rocking lever, the lower end of which is pivoted to the base by a link connection (not shown) and 45 the upper end of which is pivoted to and operates a crosshead 4. A pitman 5 is pivoted at one end to the rocking lever, and its other end engages the crank pin 6 of the crank wheel 7.

50 The machine is preferably driven by a belt running on the tight pulley 8 which with its coacting loose pulley 9 is mounted on one end of the shaft 10, journaled on frame 2. On the other end of shaft 10 55 is the driving pinion 11 which meshes with

crank wheel 7 on shaft 18. A toothed wheel 13 which is actuated from shaft 18 is secured on shaft 14 journaled on frame 2. On the farther end of shaft 14 is a pinion 15 meshing in gear 16 on the rotary pattern 60 shaft 61, and said gear 16 meshes in gear 17 on shaft 61^a of the coacting rotary pattern. Shaft 18 carries a switch wheel 19 which operates the yarn changing device, to be described farther on, and a second 65 switch wheel 20 through which the wheel 18 is operated. The needle beds are preferably of the composite type, consisting of the wall plates 23 and bottom plates 24 held in series between two blocks 25-26 which 70 are fastened to frame 2, at an inclination of about thirty degrees. The cam bars 27-28 move in suitable grooves in the needle beds; the driven ends are fastened to the cross head 4 and receive motion from the rocking 75 lever 3. On the under side of each cam bar is fastened the needle retracting cam 29 and the needle projecting cam 30.

The usual construction in straight knitting machines is to have the entire retracting cams movable for adjustment and usually the cam is made in two pieces. It is seen that the main body of my cam is in one piece which is fastened rigidly to the cam bar, to which it belongs, and the adjustment in the knitting is made by providing the cam with points 29^a-29^b located at the ends of the cam. It is seen that when the points 29^a-29^b are turned forward into the dotted position, the needles operated upon 80 by the jacks 31 will be drawn back farther than if the points were in the full line position, and hence knit looser, and when turned back in the opposite direction, the needles will not be drawn down so far, and hence 85 will knit tighter. These adjustable points are conveniently formed on the edge of two disks 29^c secured on studs 29^d and held in circular bearings in the cam bar, and by means of their studs passing through the 90 cam bar and the connecting levers 29^e and 29^f attached to the studs, the points can be turned in either direction as desired. The 95 lever 29^e has a handle 29^g whereby both levers may be operated in unison, and both the 100 adjusting points similarly adjusted, and the handle has a spring which engages a rack 105 29^h and thereby locks the levers in their adjusted position. The jacks 31 are controlled by corresponding vibrating levers 32 pivoted 110

at the lower edge of the needle bed, and having feet 32^a resting on one of the rotary patterns. When the needles are desired to work, the pattern holds the lever up and also 5 holds the corresponding jacks in reach of the knitting cams, and when the needles have done their duty and are desired to remain inactive, they pass entirely off of the pattern which is cut away from that point up to 10 the point at which the needles resume work. A spring 33 or other proper means acting on lever 32 forces the lever down as soon as it ceases to be supported by the pattern and with it causes the jacks 31 to be drawn 15 out of reach of the knitting cams. I prefer to make the rotary pattern by casting it with only such amount of acting surface as is required to make the necessary pattern, as will be seen from Figs. 2 and 7. A stop 32^b is 20 fastened to the needle bed and limits the downward movement of the vibrating levers, which serves the purpose of a lower surface plane upon which their feet may travel when the needles are inactive. This construction 25 makes a cheap and very much lighter rotary pattern than those heretofore used.

I have shown the pattern required for half hose in which the notched or stepped part from *c* to *d* forms the toe pattern; 30 that part from *d* to *e* forms the foot portion; that part from *e* to *f* is the first half of the heel pattern, and a corresponding portion not shown forms the other half of the heel. The patterns may be described as 35 forming mutilated drums or cylinders having a large and irregular part to wit, the non-acting portion of their walls or peripheries cut away. They are supported from their shafts by arms 65. It should be noted 40 that the notches shown vary with the gage of the machine, running from $\frac{1}{4}$ inch in four gage, to $1/20$ inch in sixty gage. The shafts 61 and 61^a supporting the rotary patterns are held in the bearings 61^b pivoted 45 in frame 2, and as it is desirable that the rotary patterns to be easily adjusted to the proper height with reference to the vibrating levers 32, I do this conveniently by making the bearings 61^b adjustable, placing 50 supporting screws 62-63 above and below them and attaching the bearings to pivoted arms 64 as shown in Fig. 1. This construction of the bearings, also permits the removal of the patterns at any time when 55 necessary or desirable for change of the pattern or for repair, without disturbing the needle bed.

Gears 16-17 which mesh together are fastened upon the rotary pattern shafts 60 whereby the shafts are caused to move in unison. Their movements are, however, intermittent inasmuch as the toothed wheel 13 through which they are actuated is moved intermittently by the switch wheel 20 which 65 is fastened on shaft 18.

Motion is given to the toothed wheel 13 by the swinging of the switch sections 34, 34^a forming part of the central upstanding rib on wheel 20. These switch sections are so placed that the movements caused by 70 them shall occur near the end of the cam bar movements. When switch 34 is moved to stop stud 35 the end of the switch engages a tooth of wheel 13 and moves the wheel forward one step, so that the stationary or non-adjustable portion of the rib which follows said switch will engage the next tooth of wheel 13. When in the continued movement of the wheel 20, the other switch is similarly opened, the wheel 13 75 is shifted another step, and these operations are repeated indefinitely.

In certain kinds of work, it is desirable to turn the pattern backward and when this occurs the switches are turned out in the 80 other direction to stop stud 36 so that wheel 13 is operated backward, the operation being exactly similar to that above set forth except that it is reversed in direction. To adapt the vibrating levers 32 to the backward movements of the pattern cylinders, the feet 32^a are beveled upon both their front and back faces so that they will be lifted from positions off the cylinder up on to the surface of the same whenever that 95 is necessary in either the forward or back rotations.

The mechanism for shifting the movable switch sections upon wheel 20 is desirably constructed as follows: At 470 is a shaft on 100 which is mounted the ratchet plate 44, which is operated by a pawl 45 pivoted to a lever 46, the end of which enters the groove of cam 47 on shaft 18. This cam is adapted to impart a to and fro movement to the 105 pawl and thus cause it to turn the plate 44 step by step. At 40 is a lever, pivoted stationarily at its rear end in an arm 400 and having a foot at the other end which rests upon the control plate 43 attached to 110 the ratchet plate, and this plate 43 has teeth forming three different planes adapted to support the foot in different positions, and by these different positions the position of an arm 38 whereby the switch sections 115 are operated, is regulated. The three positions mentioned consist of the top of the teeth of plate 23, the intermediate shoulders shown as being formed on the teeth (the foot is shown at Fig. 12 as resting on one 120 of the shoulders) and the bottoms of the separating spaces between the teeth. The lever 40 is connected by a link 41 to a crank 42 on a rock shaft 39 on which is fastened the arm 38 already mentioned, and on which 125 are cam blocks 38^a and 38^b. This shaft 39 is parallel to shaft 18, and sufficiently near to it so that the arm 38 may swing against and through said cams operate the arm 37 projecting from the switch sections. The 130

latter are pivoted upon pivots 82, so that when the arm 37 which is also pivoted at 83 is engaged by the cams, the switch section will be swung either toward the stop 36 or 5 toward the stop 35, depending upon which cam engages the arm 37. The positioning of lever 40 by the teeth of plate 43 determines which cam of arm 38 shall operate on the switch section, and the cam determines 10 the direction in which the section shall be moved. The tips of the teeth of control plate 43, the intermediate shoulders of the teeth, and the recesses between the teeth all impart varying degrees of throw to the arm 38, in one of which the cam 38^a is positioned to operate the switch section, in another of which the cams are rendered neutral, being positioned so they do not engage the arm 37, and in the last of which 15 20 the cam 38^b is positioned to operate the switch section in the reverse direction from that imparted by cam 38^a.

The yarn is delivered to the needles by the yarn carrier 49 which is moved back and forth by the driving bar 50 fastened adjustably to a bar on the cross head, and is adapted to feed the yarn to either row of needles or to both rows at once as in setting up the work, the movement of the 25 30 needles being controlled by the pattern. It is desirable at times to change the yarn while the machine is in motion, and for this purpose a series of yarn carriers are provided as 49—49^a 49^b which are held in a transfer bar 51 supported by the bed piece 52 at right angles to the passage of the cam bars. At each round the carriers are 35 40 brought into one of the receiving grooves 53, 54, 55 or 56 of the transfer bar. These grooves are all adapted to be moved into register with the yarn carrier grooves in the needle bed, and the guide carriers have their ends bent up at right angles so that they are adapted to catch under the overhanging lip of the driving bar 50. (See Fig. 15). The sides of the driving bar being open, the carriers are free to engage and disengage themselves when moved sidewise by the transfer bar. If the transfer bar is 45 50 moved, the carrier then in register with the groove of the needle bed will by the movement be carried out of register and another moved into register, the former disengaging itself from the driving bar and the latter taking its place in engagement therewith. The disengaged carrier will remain at rest in the transfer bar, and the newly engaged 55 60 guide enter into service. It is desirable at times to drop the fabric from the needles, and this is conveniently done by bringing an empty groove of the transfer bar in register with the driving bar when the needles will operate without yarn and the fabric drop therefrom.

65 The transfer bar 51 is conveniently op-

erated by the lever 57 pivoted on stud 58, the lower end of the lever being in the form of a toothed segment 60 meshing in the switch wheel 19, and the upper end of lever being connected to the transfer bar 70 by the link 59. It is seen that when the switch 19^a on wheel 19 is moved to the stop stud 19^b, it engages a tooth of the segment 60 and moves the transfer bar one space to the right; and when the switch is moved to stop stud 19^c it engages a tooth of segment 75 80 85 90 95 100 105 110 115 120 125 130 135 140 145 150 155 160 165 170 175 180 185 190 195 198 200 205 210 215 220 225 230 235 240 245 250 255 260 265 The working of knitting machines of this type is so well known that I have thought necessary only to describe the novel features of my invention.

What I claim is:

1. The combination of a needle bed formed substantially of wall plates and bottom plates held together in series to form grooves in which the needles shall move, jacks to operate the needles, vibrating levers to control the jacks, means to hold the vibrating levers in their lowest position, a fixed stop to limit the downward drop of the vibrating levers, and a rotary pattern cylinders movable in either direction, and upon which said levers ride, a toothed wheel geared to the cylinders, a switch wheel arranged at right angles to said wheel and having a peripheral rib engaging the same, said rib embodying a movable section, a vibrating lever for shifting said movable section, blocks carried by said lever whereby it is adapted to impart different movements to the section, and means for actuating the vibrating lever.
2. The straight knitting machine wherein are combined knitting needles held in stationary beds, jacks operating the needles, vibrating levers controlling the jacks, rotary pattern cylinders movable in either direction, and upon which said levers ride, a toothed wheel geared to the cylinders, a switch wheel arranged at right angles to said wheel and having a peripheral rib engaging the same, said rib embodying a movable section, a vibrating lever for shifting said movable section, blocks carried by said lever whereby it is adapted to impart different movements to the section, and means for actuating the vibrating lever.
3. The combination of a driving gear, adapted by proper means, to operate a knitting mechanism, a cam groove wheel on the driving shaft, a rocking arm controlled by said cam, a pawl pivoted on said rock-

- 5 ing arm, a ratchet plate adapted to be moved step by step by the pawl, a pattern plate with teeth of unequal height fastened to the ratchet plate, a lever provided with a foot adapted to rest on the pattern teeth, means to connect this lever with a rocking shaft, an arm provided with cam blocks (38) fastened to said rocking shaft, whereby a driving switch may be controlled in a central, right, or left position adapted to leave the rotary pattern at rest, or move it forward or backward as desired.
- 10 4. The combination of a revolving switch wheel provided with a swinging switch, a lever provided with a toothed segment pivoted centrally over the switch wheel, a link connecting the lever to a yarn carrier changing bar provided with two or more receptacles for yarn carriers and means for moving the switch to the right or left of its central position whereby the yarn carrier bar can be moved in either direction as desired.
- 15 5. In a straight knitting machine, the combination with the needles, the needle jacks, the parallel beds in which the needles are supported, the horizontal rotary patterns arranged parallel with the beds and rotating in both directions, means for rotating the patterns in both directions, and vibrating levers controlling the jacks and having feet beveled both in front and rear adapting them to ride up on to the patterns whether they are rotated forward or back.
- 20 6. In a straight knitting machine, a needle retracting cam composed of a central stationary part, adjusting points at each end of said stationary part, and means for adjusting said points together in unison.
- 25 7. In a straight knitting machine, a needle retracting cam composed of a central stationary part, adjusting points at each end of said stationary part mounted on oscillating supports, and means for oscillating both
- 30 points in unison.
- 35 8. The straight knitting machine having a needle controlling pattern rotating on a horizontal axis, the end of said pattern being notched by cutting away the parts
- 40 50 which allow the needle to be inactive, in combination with actuating mechanism adapted to rotate said pattern in both directions.
9. The straight knitting machine having a rotating mutilated pattern cylinder, the operating parts of which are fixed, in combination with automatic controlling mechanism moving said cylinder in both directions.
10. The straight knitting machine where-
in are combined knitting needles held in stationary parallel beds, jacks operating the needles, vibrating levers controlling the jacks and riding upon rotary pattern cylinders arranged parallel to the beds and having feet beveled both in front and rear, thus adapting them to lift the levers from positions off the cylinders to positions on the top of the same whether the cylinders are turned forward or back, said cylinders being movable in either direction, a toothed wheel geared to the cylinders, a switch wheel having a peripheral rib engaging said toothed wheel, said rib embodying a movable section, a device for shifting said movable section provided with means whereby it is adapted to shift the section in different directions, and means for actuating the shifting device.
11. A straight knitting machine wherein are combined knitting needles held in parallel stationary beds, jacks operating the needles, vibrating levers controlling the jacks, rotary pattern cylinders arranged parallel to the beds and movable in either direction, said levers having feet beveled both in front and rear, and riding on the cylinders and being adapted to lift the levers from positions off the cylinders to positions on top of the same, whether the cylinders are turned forward or back, a toothed wheel geared to the cylinders, a switch wheel having a peripheral rib engaging said wheel, said rib embodying a movable section, devices for shifting said movable section adapted to shift it in both directions, and means for actuating the shifting devices.
